UNITED STATES PATENT OFFICE.

WALTER SCHOTTKY, OF WURZBURG, GERMANY, ASSIGNOR TO SIEMENS-SCHUCKERT-WERKE GESELLSCHAFT MIT BESCHRANKTER HAFTUNG, OF SIEMENSSTADT, NEAR BERLIN, GERMANY, A CORPORATION OF GERMANY.

RELAY SYSTEM.

Application filed November 2, 1920. Serial No. 421,396.

(GRANTED UNDER THE PROVISIONS OF THE ACT OF MARCH 3, 1921, 41 STAT. L., 1313.)

To all whom it may concern:

Be it known that I, WALTER SCHOTTKY, a citizen of the German Empire, residing at Wurzburg, Germany, have invented certain new and useful Improvements in Relay Systems, (for which I have filed applications in Germany July 12, 1916, June 30, 1917, July 17, 1918, and Aug. 18, 1918; in Hungary, June 28, 1917; Austria, June 23, 10 1917; Sweden, Dec. 23, 1919; Norway, Dec. 24, 1919; Denmark, April 21, 1920; Switzerland, May 18, 1920; France, May 21, 1920; Holland, June 4, 1920; Italy, June 29, 1920; Poland, July 7, 1920; Czechoslovakia, June 15 23, 1920), of which the following is a specification.

This invention relates to an improved form of connection for electric current amplifiers and more particularly for thermionic repeaters arranged in cascade such as are employed in connection with telephony, telegraphy and the like. In the case of connections of this kind, there are generally arranged in front of the first and to the rear of the last amplifier, and also intermediate the several amplifiers, transformers for the purpose of transmitting the amplified alternating current only. Now, such a large number of transformers cannot in most cases be disposed so as to avoid mutual interference with each other. These influences are partly due to the magnetic stray fields; besides such transformers are mutually interconnected by the capacity of their windings, relatively to each other and to the earth. By reason of these two causes there are produced disturbances which make themselves disagreeably perceptible either by loud noises, or by the singing or howling of the entire system. In the event of the necessity of surrounding the transformers with iron jackets for the purpose of providing a magnetic protection, the inherent considerable losses sustained in such 40 transformers are further increased to a large extent.

It has already been proposed to substitute for the transformers a combination of a choking coil or ohmic resistance in the output circuit of one amplifier with a battery in the input circuit of the succeeding amplifier, the said circuits being directly

connected to each other and the battery serving to counterbalance the direct current in the output circuit of the preceding 55 amplifier. Such an arrangement has, however, the disadvantage that the regular working of the connection depends greatly upon the constancy of the battery potentials; since this latter, however, fluctuates 60 no satisfying results are obtained with such devices.

It has further been proposed to use in the output circuit of the amplifiers a choking coil and to connect this output circuit to the input circuit of the following amplifier over a capacity. Such an arrangement has the disadvantage that on account of the 70 choking coil it is too selective for several purposes.

According to the present invention ohmic resistances are inserted in the output and input circuits and the connection between the output and input circuits is made over a capacity. The use of ohmic resistances 75 offers the distinct advantage that the connection produces for all frequencies the same amplifying effect since in contradistinction to choking coils, oscillatory circuits or transformers and similar expedients, ohmic resistances are entirely independent of the frequencies. For this reason a connection in which resistances are employed 80 will prove particularly suitable for amplifying telephone currents.

Special advantages will furthermore result in cases where it is a question of amplifying alternating currents of low frequencies, say, of about 50 periods by second. In such a case, choking coils or transformers employed for obtaining sufficiently large impedance values would require such a quantity of iron or copper windings that ohmic resistances will be found to be far superior, insofar as saving in weight and 95 material are concerned. Finally attention is also directed to the fact that ohmic resistances are preferable for the reason that they embody no magnetic fields, as compared with choking coils or similar expedients which produce disturbances caused by feed-back phenomena.

However, also in the case of other installations operating with but one frequency, such

as wireless or similar signalling arrangements, and where this frequency is altered from time to time, a connection of the character described, embodying resistances, has 5 certain advantages because, owing to the degree of amplification being independent of the frequency, a special setting of the amplifying circuit to a maximum degree of amplification will not be required, whereby again 10 the necessity of adding further devices, requiring syntony with the requisite tuned elements of these circuits, such as antenna, resonance circuit, etc. will be obviated.

Ohmic resistances will moreover be found 15 especially suitable in cases where it is a question of faithfully reproducing signals, because of their non-selective properties. It is essential in this case that the resistances be always suitably dimensioned. According 20 to the present improved arrangement they are so chosen that the capacity and the resistances, within the anode and the service circuit will form a system the damping period of which exceeds the duration of the 25 signal transmitted. In such case, resistances of an extremely high value must be employed. They are considerably larger than those used in an ordinary connection. Thus, for example, in the case of an average transmitting speed, there will be obtained for 30 a damping period of one second, one microfarad for the condenser and one megohm for the ohmic resistance.

An embodiment of my present invention 35 is shown in the accompanying drawing in which a connection of thermionic tubes by means of ohmic resistances and capacities is represented in diagrammatic form.

In the drawing a connection for three 40 amplifier tubes E_1 — E_3 is disclosed. In the case shown these tubes are provided each with a special set of batteries B_1 — B_3 . The individual amplifiers are connected with each other and with the receiving instrument T by a single line only while their second pole is earthed. Within the single junction line are arranged the condensers C_1 — C_3 .

The ohmic resistances d_1 — d_3 are lodged within the output circuits in the amplifiers including the plates p_1 — p_3 and filaments f_1 — f_3 respectively. Their value must be equal to that of the tube resistance to enable possible fluctuations of voltage to be transferred on to the grids h_1 — h_3 . By means of the ohmic resistances r_1 — r_2 the 55 negative potential of the battery appertaining thereto is connected to the auxiliary electrode or grid of the respective amplifier.

Of course the invention is not restricted to the exact conception of the conventional amplifier element shown, for instance the individual batteries, which may be grouped and connected in any other suitable way known in the art.

I claim:—

1. In a connection for alternating current or direct current impulse amplifiers, each having an input and an output circuit and a source of direct current contained in the output circuit, an ohmic resistance in the output circuit of each amplifier, a capacity in the connecting line between the output circuit of one amplifier and the input circuit of the succeeding amplifier and an ohmic resistance inserted in the input circuit of 75 each amplifier.

2. In a connection for alternating current or direct current impulse amplifiers, each having an input and an output circuit and a source of direct current contained in the output circuit, an ohmic resistance in the output circuit of each amplifier, a capacity in the connecting line between the output circuit of one amplifier and the input circuit of the succeeding amplifier and an ohmic resistance inserted in the input circuit of each amplifier, the said ohmic resistances and capacities of connected output and input circuits being chosen to form a system, the damping period of which exceeds the duration of the signal to be transmitted.

In testimony whereof I affix my signature.

WALTER SCHOTTKY.
